(57) **CLAIM**

The ornamental design for a swivel opening drinkware lid as shown and described.

DESCRIPTION

FIG. 1 is a side perspective view of a swivel opening drinkware lid in a closed configuration according to the new design.

FIG. 2 is a top plan view thereof.

FIG. 3 is a bottom plan view thereof.

FIG. 4 is a front elevation view thereof.

FIG. 5 is a rear elevation view thereof.

FIG. 6 is a right side elevation view thereof.

FIG. 7 is a left side elevation view thereof.

FIG. 8 is a side perspective view of the swivel opening drinkware lid of FIG. 1 in use with the environment of a drinkware container.

FIG. 9 is a side elevation view thereof.

FIG. 10 is a top plan view of the swivel opening drinkware lid of FIG. 1 in an open configuration; and,

FIG. 11 is a right side elevation view thereof.

The shade lines in the Figures show contour and not surface ornamentation. The broken lines in the Figures show portions of the swivel opening drinkware lid that form no part of the claimed design. The broken lines in FIGS. 8 and 9 illustrate the environment of a drinkware container that forms no part of the claimed design.
